UNITED STATES PATENT OFFICE

WILLIAM L. COOPER, OF KANKAKEE, ILLINOIS, ASSIGNOR TO SEARS, ROEBUCK AND CO., OF CHICAGO, ILLINOIS, A CORPORATION OF NEW YORK

DESIGN FOR A COOKING STOVE

Application filed November 12, 1928. Serial No. 28,841. Term of patent 7 years.

To all whom it may concern:

Be it known that I, WILLIAM L. COOPER, a citizen of the United States, residing at Kankakee, in the county of Kankakee and State of Illinois, have invented a new, original, and ornamental Design for a Cooking Stove, of which the following is a specification, reference being had to the accompanying drawing, forming part hereof.

Fig. 1 of the drawings is a front elevation of a cooking stove embodying my new design.

Fig. 2 is a perspective view of the front of the cooking stove.

Fig. 3 is a fragmentary cross section of a part of the stove taken substantially on the line 3—3 of Fig. 1.

The dominant feature of the invention resides in the provision of a burner skirt in the form of a combined vertical and forwardly extending horizontal partition extending across the burner compartment of the stove.

I claim:

The ornamental design for a cooking stove, substantially as shown and described.

WILLIAM L. COOPER.
